Primary Examiner—B. J. Bullock(74) *Attorney, Agent, or Firm*—Pearne & Gordon LLP(57) **CLAIM**

The ornamental design for a self-piercing clinch nut, as shown and described.

DESCRIPTION

FIG. 1 is a perspective view of a self-piercing clinch nut including a plurality of lugs spaced about a central pilot, showing our new design;

FIG. 2 is a top plan view thereof;

FIG. 3 is a vertical cross-sectional view taken in the direction of the arrows on line 3—3 of FIG. 2;

FIG. 4 is a bottom plan view; and,

FIG. 5 is a side elevational view.
